UNITED STATES PATENT OFFICE.

CHARLES H. A. F. L. ROSS, OF BALNAGOWAN CASTLE, ROSS COUNTY,
SCOTLAND.

RECOIL-OPERATED FIREARM.

SPECIFICATION forming part of Letters Patent No. 643,983, dated February 20, 1900.

Application filed April 30, 1897. Serial No. 634,558. (No model.)

To all whom it may concern:

Be it known that I, CHARLES HENRY AUGUSTUS FREDERICK LOCKHART ROSS, baronet, of Balnagowan Castle, county of Ross, 5 Scotland, have invented certain new and useful Improvements in Small-Arms and Machine-Guns, (for which I have obtained Letters Patent in Great Britain, No. 5,683, of March 13, 1896, on application filed March 13, 10 1896, and sealed June 29, 1897,) of which the following is a specification.

The object of this invention is to simplify the construction of breech-loading firearms, and more especially of recoil-firearms and 15 machine-guns, and the invention relates more particularly to that class in which the bolt-head is provided with lugs which enter recesses in the breech end of the barrel and the head is automatically rotated by the longitudinal motion thereof to cause the lugs to catch behind shoulders, whereby the parts are locked together.

In the accompanying drawings, Figure 1 is a side view, partly in section, of a small-arm 25 constructed according to my invention with the breech closed, only so much being shown as is necessary to illustrate this invention. Fig. 2 is a longitudinal section showing the breech open. Fig. 3 a section on the line 30 1 2, and Fig. 4 is a section on the line 3 4, both of Fig. 1. Fig. 5 shows in side and edge views the bolt-catch. Figs. 6, 7, 8, 9, and 12 show detached views of the bolt as used for a small-arm, and Figs. 10 and 11 show detached views of the bolt as employed for a 35 machine-gun.

The present invention consists more especially in the means employed for rotating the bolt-head, though there are other features 40 which aid to simplify the construction. The barrel slides backward and forward in a shoe, in which also the bolt is located, with the springs for operating the bolt. The barrel-spring is preferably outside the shoe. The 45 bolt consists of two parts—a sleeve and a rotating head. This head is provided with two pins which fit into and work in spiral slots in the sleeve, and the movement of the sleeve in a forward direction rotates by means 50 of these slots the bolt-head and causes it to lock into the barrel.

The bolt and barrel recoil together locked and a catch retains the sleeve. The barrel, which is still locked to the head, as it returns draws the head with it, and by reason of the 55 slots in the sleeve the head is caused to rotate and unlock from the breech. The barrel then runs forward and when near its normal position it releases the sleeve, which being propelled forward by its spring causes the head 60 to again enter the breech.

The period of time between the unlocking of the head and the releasing of the sleeve is sufficient to allow a cartridge to rise from the magazine into the line of the bolt, which 65 drives it into the barrel as it goes forward.

On pulling the trigger the sleeve is driven forward, (if it has not been already moved to the limit of its movement in that direction,) and thus first rotates the head in the breech-piece to lock it and then fires the cartridge by means of a firing-pin carried by the sleeve and projecting through the head, the parts being so arranged that the locking shall be securely effected before the pin strikes the 75 cap.

When it is desired to load by hand, the barrel is jammed in the shoe in any convenient manner, and the bolt can be pulled back and driven forward by a hand-lever secured to the 80 sleeve, the diagonal slots in the sleeve serving to lock and unlock the head. A suitable extractor and ejector will be employed, and the cartridges will rise through a slot in the shoe in the usual manner.

A is the barrel, and A' represents one form of the barrel-spring, which is compressed when the recoil takes place, as is now well understood.

A² is the bolt-spring, which is attached to 90 the bolt by a rod A³, and is shown outside the barrel for convenience; but it may be placed in any other convenient position.

B is a tubular shoe in which all the moving parts work, the said shoe being bolted to 95 the fore end B' and supported at the rear end by a bracket B², carried by the trigger-plate or in any other suitable manner. This shoe B is cut away at top for nearly its whole length, and at bottom it has two slots B³ B⁴, 100 one for the cartridge to come through from the magazine and the other for the hammer

to work through. Besides these the shoe has a longitudinal slot B⁵ in the side for a purpose to be presently explained.

The barrel A is screwed into a breech-piece 5 C, which is provided with a tubular rearward extension C', which is cut away at top and has two slots in bottom corresponding to those of the shoe B. Near its forward end the extension C' of the breech-piece is recessed internally, as at C², to form shoulders C³, and on each side of the inner face of the extension is formed a longitudinal groove c, extending rearwardly from near the corresponding recess C² to the end of the extension. On the outside of this extension are pins C⁴ C⁵, which both work in the slot B⁵ and are intended to operate on opposite sides of a catch, as will be presently explained. In this breech extension C' works the bolt, which is formed of 15 two parts—a sleeve and the bolt proper. D is the sleeve to which the handle D' is firmly secured. On one side of this sleeve and extending forward about two-thirds of its length from its rear end is a feather D², which works 20 in one of the longitudinal grooves c of the extension C', and in the front end of this sleeve are two inclined slots D³, the use of which will be presently explained. On the top of the sleeve at its front end is secured a block E, 25 which has on one side a feather E', to slide in the other of the longitudinal grooves c in the extension C', and a laterally-extending finger E², which overlies and slides on the top edge of the cut-away portion of both the shoe and 30 the extension C'. To this finger E² in the present instance the bolt-spring or its rod is attached by means of the screw-pin E³.

G is the bolt proper, which contains the firing-pin G' in the usual way. The bolt is 35 formed with a head G² of increased diameter—that is to say, of the diameter of the sleeve—having two lugs G³ on opposite sides, and at the rear end a collar G⁴ is screwed on. In front of the collar is a loose ring G⁵, carrying 40 a radial pin G⁶, onto which the extractor II is fitted. In the sides of the bolt are fitted pins G⁷, which work in the inclined slots D³ of the sleeve D, so that by pushing the sleeve forward the bolt is rotated on its axis.

45 The extractor II consists of a strip of spring metal slightly curved, so as to fit snugly against the side of the sleeve and the bolt-head, and it has a hole at its rear end which fits onto the pin G⁶ of the loose ring G⁵. 50 When in its proper position, the extractor lies in a notch formed in the block E, as will be seen in the end view of the bolt and sleeve, Fig. 6. The end of the strip is hammered over to form a catch for the rim of the cartridge.

55 The locking-lugs G³ of the bolt-head G² enter the recesses C² of the breech-piece, and at the proper moment the bolt-head is rotated, so that the lugs G³ will catch behind the shoulders of the recess, and thus lock the head to the barrel.

Fig. 7 shows the bolt in the unlocked po-

sition, and Figs. 8 and 9 the bolt in the locked position.

J is a curved catch which is fitted to slide vertically in the guides j outside the shoe, (see Fig. 1,) and this catch is shaped as shown in the detached views, Fig. 5. From Fig. 1 it will be seen this catch spans the slot B⁵, in which the pins C⁴ C⁵ of the extension C' work, so that when the pin C⁵ strikes the cam-face on the front side of the catch J the catch will be raised into the path of and will hold the finger E² of the sleeve D. When the pin C⁴ strikes against the rear cam-face of the catch J, the catch will be depressed, so as to free the finger E² of the sleeve.

K is a pin fitted on the inside of the extension C', (see Fig. 2,) which will strike against the rim of the cartridge as the barrel and extension C' go forward under the influence of the barrel-spring and the cartridge will be kicked out, so that this pin may be designated the "ejector."

The operation of the parts will be as follows: A cartridge having been fired, the recoil will cause the barrel to run back with the bolt locked until the pin C⁵ strikes against the catch J, which will be raised to hold the finger E². The compressed barrel-spring now acts to drive the barrel forward, carrying with it the bolt-head. As the bolt-sleeve is held by the catch J, the forward motion of the barrel will rotate the bolt-head by means of the pins G⁷ and the slots D³ and the head will be thus unlocked, the barrel continuing its forward motion without the bolt. The extractor being stationary with the sleeve holds the cartridge-case until the forwardly-moving pin K strikes the rim and kicks the case out. A fresh cartridge now rises from the magazine (which may be of any suitable kind placed in the space L) into line with the bolt. The pin C⁴ now strikes the catch J and draws it down, releasing the bolt-sleeve D, which is drawn forward by the bolt-spring. This drives the cartridge into the barrel and the bolt-head into the breech. The continued forward movement of the sleeve rotates the bolt-head in the recess C² and causes the lugs G³ to take behind the shoulders and the bolt is locked. The arm is now ready for firing by pulling the trigger. The hammer is automatically cocked when the parts are driven back by the recoil.

In adapting the invention to a machine-gun I may dispense with the hammer and trigger; but in all other respects the mechanism generally will be the same as above described for the hand-gun.

If the hammer is not used, I adapt to the sleeve D an extension-piece M in the form of a stirrup, which carries a stump or pin M', and I arrange the slots D³ so as to close the breech a little before the sleeve is home, as indicated in Fig. 10. The continued forward movement of the sleeve to get home will force the firing-pin onto the cap of the cartridge, and thus fire it. The recoil will act to reload and fire and the motion will continue as long as

there are any cartridges in the magazine. Any desired number of these barrels will be mounted in a suitable carriage and will be provided with a convenient magazine arrangement; but as these form no part of the present invention further description is unnecessary.

I do not in this application claim a hammer and a movable safety-stop, the stop preventing the contact of the hammer with the firing-pin, while the breech-bolt is unlocked and moved by the hammer to lock the breech-bolt and to uncover the firing-pin for contact with the hammer, or any claim specific thereto, as I make such a claim in my other application, serially numbered 664,364, filed December 29, 1898; but

What I now claim is—

1. In a breech mechanism the combination with a breech-piece, of a breech-bolt longitudinally movable therein, a longitudinally movable extractor, and an ejector projecting laterally from the inner wall of the breech-piece and adapted to strike the base of the cartridge and eject it, substantially as described.

2. In a recoil-operated gun, the combination with a fixed shoe, of a catch, a breech-bolt and a barrel longitudinally movable in the shoe, the barrel having projections thereon for actuating the catch and causing it to engage and disengage the breech-bolt, substantially as described.

3. In a recoil-operated gun, the combination with a slotted fixed shoe, a sliding catch having inclined faces thereon spanning the slot in the shoe, a barrel sliding within the shoe and having pins thereon adapted to engage the opposite sides of the catch, and a breech-bolt, caught and released by the said catch as the latter is engaged by the one or the other of the pins upon the barrel, substantially as described.

4. In a breech mechanism for a recoil-operated gun, the combination with a fixed shoe, of a longitudinally-movable breech-piece, and a longitudinally-movable sleeve and breech-

bolt therein, the breech-bolt comprising a revoluble bolt-head adapted to be locked to and unlocked from the breech-piece by the longitudinal movement of the sleeve, and a catch, thrown into engagement with the sleeve by the rearward movement of the breech-piece and disengaged by the forward movement thereof, and means for returning the longitudinally-movable parts to normal position when they have been driven rearwardly by the recoil, substantially as described.

5. In a breech mechanism for recoil-operated guns, the combination with a fixed and slotted shoe having guides on the exterior surface thereof, a catch sliding in the said guides and spanning the slot in the shoe, the said catch having correspondingly-inclined driving-faces on the opposite sides thereof, a breech-piece longitudinally movable in the shoe and having pins thereon projecting through the slot thereof and contacting with the opposite driving-faces of the catch, and a breech-bolt longitudinally movable in the shoe and having a projection thereon engaged by the catch and disengaged from the catch, according as the latter has been driven by one or the other of the pins upon the breech-piece, substantially as described.

6. In a breech mechanism for firearms the combination with a breech-piece, of a headed breech-bolt, locked to the breech-piece by a rotative movement, a firing-pin contained in the headed breech-bolt and projecting to the rear thereof, a sleeve longitudinally movable in respect to said firing-bolt, and having an anvil to contact with the rear end of the firing-pin, and a projection and a spiral slot for rotating the breech-bolt by the longitudinal motion of the sleeve, the slot having a longitudinal extension to permit the continued movement of the sleeve after the bolt has been locked, whereby the firing-pin will be actuated, substantially as described.
